CLAIM

The ornamental design for an electric blender, as shown and described.

DESCRIPTION

FIG. 1 is a perspective view of an embodiment of an electric blender showing my new design;

FIG. 2 is a front elevational view of the electric blender of FIG. 1;

FIG. 3 is a rear elevational view of the electric blender of FIG. 1;

FIG. 4 is a right side elevational view of the electric blender of FIG. 1;

FIG. 5 is a left side elevational view of the electric blender of FIG. 1;

FIG. 6 is a top view of the electric blender of FIG. 1; and,

FIG. 7 is a bottom view of the electric blender of FIG. 1.

(Continued)

The broken lines shown in the figure drawings are for the purpose of illustration and form no part of the claimed design.
